Patented Nov. 30, 1965

203,047

OPTICAL CHARACTER READER

Edward J. Sabella and Jack K. Hockenberry, Vestal, N.Y.,
assignors to International Business Machines Corpora-
tion, New York, N.Y., a corporation of New York

Filed Feb. 26, 1965, Ser. No. 83,992

Term of patent 14 years

(Cl. D26—5)

FIG. 1

FIG. 3

FIG. 2

Des. 203,047

PAGE 5

FIG. 4

FIG. 5

FIG. 6

FIG. 1 is a front perspective view of an optical character reader showing our new design.

FIG. 2 is a front elevation view of the same.

FIG. 3 is a top view of the same. The grill member partially illustrated is understood to be continuous throughout said portion.

FIG. 4 is a rear view of the same.

FIG. 5 is a left side view of the same.

FIG. 6 is a right side view of the same.

The dominant features of our design reside in those portions shown in full lines on the drawing.

We claim:

The ornamental design for an optical character reader, as shown and described.
